UNITED STATES PATENT OFFICE.

ARTHUR WHITE BRETLAND, OF DUBLIN, IRELAND.

LAYING OR TAKING UP OF RAILWAY TRACKS.

Application filed November 6, 1924. Serial No. 748,270.

To all whom it may concern:

Be it known that I, ARTHUR WHITE BRETLAND, a subject of the King of England, residing at Dublin, Irish Free State, have 5 invented certain new and useful Improvement in or Relating to the Laying or Taking Up of Railway Tracks, of which the following is a specification.

This invention relates to an improved 10 plant for the handling of assembled track units of railway tracks, and it has for its object to enable the laying of new railway tracks or the taking up of old railway tracks and the re-laying of railway tracks to 15 replace railway tracks previously removed to be greatly facilitated and expedited. For the conveyance of the assembled railway track units from and to an appropriate depot, a train is as usual employed comprising 20 rolling stock of a convenient type such as railway trucks, arranged in a definite order and provided with runways on or incorporated with their respective floors or decks to form a continuous runway for the conveyance thereover of the track units from one 25 end of the train to the other by means of appropriate hoisting and conveying gear, whereby the individual track units are picked up from the stacks on the trucks and 30 conveyed to a laying gear at the end of the train and placed at the requisite point of the road bed.

Now according to this invention, and in order to enable the performance of the several operations aforesaid to be effected in a simple and highly economical manner, the rails of the continuous runway on the trucks are mounted laterally preferably above the longitudinal sides of the trucks to leave the 35 space between them on the trucks unobstructed for the stacking of the track units directly on the decks or floors of the trucks and to provide a clear runway alongside of the train. Adapted to run on this continuous runway is a travelling trolley crane or gantry so constructed as to bridge or span the train transversely and to run freely over and clear of the stacked track units on the consecutive trucks from one end of the 40 train to the other in either direction. Supported at the laying end of the train over a normally empty truck is a suspended cantilever provided with a laying crab and a runway therefor along its entire length and 45 having its rear arm so constructed and overhanging the runway of the travelling gan-

try as to enable that overhanging part of the cantilever and the gantry structure to house one another or to overlap in their co-operative position.

Due to this arrangement, therefore, when the gantry has reached the laying end of the train, its conveying gear is brought into close proximity to the laying crab of the cantilever crane, and the arrangement is 50 such as to enable this co-operation to be effected between the cantilever arm and the bottom of the truck on which the cantilever is supported or over which the feed of track units takes place, with the result that the 55 laying crab and the grab on the gantry may readily feed one another with track units no matter in what direction.

The above and other characteristics of this invention will hereinafter be more fully 60 described with reference to the accompanying drawings in which:—

Fig. 1 shows diagrammatically the composition of a train for laying, relaying or taking up railway tracks according to the 65 invention.

Fig. 2 shows a complete railway truck for transporting the railway track in made up sections or units and fitted with runways and a travelling gantry for transporting 70 such units from any one of the trucks to the front of the train for laying or vice versa.

Fig. 3 is a plan view of the travelling gantry showing more particularly the driving and hoisting gears mounted thereon.

Fig. 4 is an end view of the truck and gantry as shown in Fig. 2.

Fig. 5 illustrates the crane truck fitted with a cantilever crane and shows the travelling gantry and the laying crab in their 80 co-operative positions, respectively, for either laying a new track or picking up an old one.

Fig. 6 is a plan view of Fig. 5, but showing only the truck and cantilever crane.

Fig. 7 is a sectional elevation on the line VII—VII of Fig. 8 of the rear end of the crane truck, showing the laying crab in the act of picking up a new track unit or of depositing an old one which has previously 90 been laid and is to be removed by the travelling gantry.

Fig. 8 is a plan and

Fig. 9 is an end elevation of Fig. 7.

It should be noted that the Figs. 1 to 9 100 represent more or less diagrammatic views from which irrelevant details have been

eliminated, while details of importance deleted therefrom for the sake of clearness are illustrated in the following separate drawings on an enlarged scale.

5 Figs. 10 and 11 show in elevation and plan respectively the means for connecting the runways and electric conductors of the several vehicles.

10 Figs. 12 and 13 are sections along lines XII—XII and XIII—XIII of Fig. 10 respectively.

15 Fig. 14 is a sectional elevation of mechanism enabling a limited lateral displacement of the hoisting gear on the traveling gantry to be effected.

Figs. 15 and 16 are, respectively, a plan view of Fig. 14, and a cross-section on line XVI—XVI thereof.

20 Figs. 17 and 18 show respectively a partly sectional elevation on the line XVII—XVII of Fig. 18 and a plan of a part of a frame which is suspended from the travelling gantry and provided with devices for gripping the rail sections to be hoisted.

25 Figs. 19 and 20 are cross sections on the lines XIX—XIX and XX—XX of Fig. 17 respectively.

30 Figs. 21 and 22 are cross sections and longitudinal sections respectively in vertical planes through the points of suspension of the grip frame carried by the laying crab and

35 Fig. 23 is a part plan of the same illustrating means for limited lateral displacement of the points of suspension with the object of tilting the said grip frame.

40 The arrangement of a depot whether stationary or movable for the stacking of new and used railway sleepers and rails and for the stacking of assembled new track units and assembled old track sections, and the means for handling that material and for its transfer to or from the rolling stock employed, will be fully understood by those skilled in the art, and no specific representation thereof would appear to be necessary in the accompanying drawings, and it will be obvious also without going into much detail that the actual track laying plant illustrated herein and hereinafter exhaustively described in connection more particularly with the handling and laying of a new track from a depot would, in a substantially like manner, be inversely employed for the taking up of an old trackway and the transfer of its constituents to a depot, or for the re-laying of an already existing track.

45 The various contrivances which together form the mechanical installation or portable plant for laying new, disassembling old or re-laying existing railway tracks are preferably accommodated on a number of rail vehicles connected to form a train, as illustrated, for example, diagrammatically in 50 Fig. 1. As shown the train referred to is

composed of a driving vehicle or locomotive L placed at the rear end thereof; a wagon P representing in the instance shown in the drawings a brake van and an electric power plant; a number of trucks A carrying stacks 70

of completely assembled track units RS each comprising rail sections and sleepers properly assembled together and at the forward end a truck B supporting a cantilever or bridge C and a motor driven crane crab E.

75 It will be noticed in the drawing that a truck A' is shown immediately behind the crane truck B which carries no load. This truck is normally empty and serves as a pass over truck above the deck of which the assembled

80 units RS brought forward by a travelling trolley crane or gantry D from any one of the rear trucks A, are individually positioned so that they may be placed by the

gantry below the rear arm C² of the cantilever crane C where they can be picked up by the laying crab thereof and carried forward thereby beyond the forward end of the crane truck B to be lowered on to the permanent way.

85 Another empty wagon or truck may be placed in any convenient position between the last named truck and the power or brake van for the purpose of suitably dealing with sections of old track when

90 relaying.

95 In Fig. 1 a track unit RS is shown in the act of being lowered from the forward crane arm C' of the cantilever C to the permanent way, while the travelling gantry D has

100 picked up a unit from the foremost loaded truck A and is in the act of conveying it onto the truck A', enabling it to be lowered and advanced and be placed below the cantilever arm C² on the truck B. The travelling gantry D then returns to fetch another

105 track unit from the stacks on the trucks A while the laying crab of the cantilever structure returns to pick up the track unit which has been deposited on truck B and to carry it forward for laying on the permanent way.

110 The whole of the trucks A A' B employed in a train of this kind have secured to their decks or floors or are otherwise provided with permanent runways or rails 1 forming

115 together a continuous track portable as a whole as the train travels and enabling the crane, gantry or like contrivances to move backwards and forward along the same. These runways formed by parallel rails 1

120 are best shown in Figs. 2 and 10 to 13. They are supported by brackets 2 along each side of each truck A and in rear of the leg of the cantilever crane on truck B. The

125 gauge of these runways is of a breadth allowing sufficient clearance to the sleepers of the truck units RS.

130 The gaps in these runways between consecutive trucks according to this invention are bridged over by short rail joints constructed and so connected to the fixed run-

ways 1 on the trucks as to yield to the movements of the individual trucks and generally to adapt themselves to any irregularities of the permanent railway track of the train. Inasmuch as the distance between each two coupled vehicles is liable to vary at different points under different working conditions, and such variations may, as for instance in curves, be in an opposite direction at the two sides of the vehicles, it is necessary also that these rail joints should be capable of expansion and contraction as the case may be. With these objects in view the bridge rails of which these joints are formed are each composed of two members 3 and 4, the member 3 being permanently secured to the end of the adjacent rail of the runway 1 of one vehicle and releasably to the other member 4 which latter forms a permanent part of, but is arranged to slide along the corresponding runway 1 of the other vehicle. Each bridge rail member 3 is pivotally so connected, both to the stationary rail of the runway 1 and to the corresponding slidable bridge rail member 4 as to be capable of swinging in a vertical plane and of performing also limited oscillating movements in a lateral direction. The permanent connection of the member 3 to the runway rail 1 is effected within a fork of the latter by means of a cardan joint 5, the movements of which are, however, restricted, not only in consequence of the stationary nature of the runway part of such joint, but, further, by the arrangement of laterally flared faces on the forked ends of the said runway 1 and of a stop in the form of a flange 1^a on the underside thereof whereby the lateral oscillations and the downward swinging movements of the bridge rail member 3 are appropriately limited. The flange 1^a is cut away in part to allow the member 3 to be swung back over the top when not in use.

The bridge rail member 4 is arranged to slide along the inside of the opposite runway rail (Fig. 12) being supported on the bottom flange 1^a in a guide way formed by the runway 1 and an inner lateral flange 4^a secured thereto. At its outer end the member 4 is provided with a shoe 4^b (Figs. 10 and 13) slidably supported on a plate 6 forming the top of a bracket which is rigidly secured on the vehicle or some stationary part thereof, as for instance, the bracket 2 supporting the runway 1. This end of the member 4 is moreover offset to form a tongue 4^c (Fig. 11) and the adjacent end of the bridge rail member 3 is forked and adapted to receive said tongue and thereby to align the member 3 with the member 4. One prong 3^a of the forked end of the member 3 is produced by reduction of its thickness and the other prong 3^b is formed by a part laterally offset thereto. The prongs 3^a and 3^b as clearly seen from Figs. 10 and 13, are hook-shaped and recessed to engage a horizontal pin 4^d rigidly secured in the tongue 4^c. The parts 4^c, 3^a and 3^b are, as shown in Fig. 11, outwardly tapered off to admit to a limited extent of relative lateral oscillations of the two members 3 and 4. In order to prevent the hook 3^a, 3^b from disengaging itself accidentally, a flange 4^e projecting laterally over the prong 3^b is formed on the tongue 4^c and the prong 3^b is reduced to a height enabling it to pass clear between the said flange 4^e and the pin 4^d when connecting or disconnecting the members 3 and 4.

The necessity of providing for a sliding movement between the bridge rail members 3, 4 and the runways 1 and the consequent lateral juxtaposition thereof entail for a corresponding distance a double width of tread. A gantry running on these runways and provided with the ordinary type of wheels having a sufficiently broad tread would be liable to run off the track or to twist. In order to overcome this danger the wheels 7 (Figs. 4 and 13) are formed with double treads, one 7^a of normal diameter to run on the broader gauge track formed by the runways 1 and a tread 7^b of a larger diameter to run on the inner narrower gauge track, which is formed by the bridging rails 3 and 4 on a correspondingly lower level than the runways 1. The tread 7^b thus forms a rim or flange for the tread 7^a and prevents running off or twisting of the gantry. The ends of the tread of the high level track are tapered to ensure smooth running.

At each end of the truck one runway is thus fitted with a member 3 and the other with a member 4 but in inverse order at opposite ends of the truck so that when two vehicles so fitted are brought together, the bridge rails will always be complementary.

Alongside the runways 1 but preferably below the same and secured to the brackets 2 are arranged insulated conductor rails 8 by which electric current is supplied from the power plant P (Fig. 1) to the travelling gantry D and to the laying crab E. At one end these conductors 8 are connected by means of a flexible cable 9 to a junction box 10 secured on the vehicle (Fig. 10). On the opposite truck the conductor rail has connected to it a flexible cable 9^a which is secured to the vehicle by means of a clamp 11 and is coupled to the cable 9 of the adjoining vehicle at the junction box 10. This cable 9^a is of sufficient length to freely span the normal maximum distance between the vehicles. Each conductor rail is thus connected at one end to a junction box and at the other end to a flexible cable, an inverse order being adopted at opposite sides of the vehicle so that these fittings of two vehicles

complement one another irrespective of which ends thereof may meet.

The travelling gantry D (Fig. 4) has an arch shaped structure of a span allowing 5 free clearance to the length of the sleepers of the track units RS and enabling it freely to travel on the runways 1 and the bridge rails 3 and 4.

It is driven from a motor 12 through suitable gearing (Figs. 2 and 3) of any known 10 type and chain drives engaging sprocket wheels attached to the wheels 7. Hoisting is performed by a winding drum 13 driven by means of suitable intermediate gearing 15 (clearly shown in Figs. 2 and 3) from a motor 14. The motors 12 and 14 are controlled by switches 12^a and 14^a operated respectively by chains 12^b and 14^b (provided at both sides of the gantry) and are fed with 20 electric current by the co-operation of appropriate collectors with the conductor rails 8. In order to ensure continuous supply of 25 electricity to the motors, two collectors are provided at each side of the gantry, placed at such distance apart that in passing from one vehicle to the other one conductor at each side is always in contact with a conductor rail.

An operator's platform D^a adapted to be 30 folded into the gantry is provided at each side thereof.

Suspended from the hoisting ropes 13^a which pass over rope pulleys 15 (Figs. 2 and 4) is a grip frame D' having a length 35 approximately equal to two-thirds of the length of a track unit RS. The lowering of this grip frame is effected in well known manner by gravity under brake control (not shown).

A device enabling the grip frame to be 40 laterally displaced or adjusted is shown in Figs. 14 to 16. Two each of the rope pulleys 15 at each end of the gantry are journaled in a freely rotatable manner on hubs formed 45 on a carriage 16 which is adapted to run on rails formed by transverse beams d arranged on the top of the gantry frame D. The carriage itself forms a nut for a screw 50 spindle 17 bearing in the longitudinal members of the said gantry frame and carrying rigidly mounted on it, at one end a worm wheel 18 operated by a worm 19 mounted on a longitudinal shaft 20. The shaft 20 is 55 operated in either direction by chains 21 actuating chain pulleys 21^a mounted at either side of the gantry frame within easy 60 reach of the operator, on transversely arranged shafts 22 which are operatively connected to the said shaft 20 by means of bevel gears 22^a and a chain drive 23.

The grip frame D' showing the means for 65 gripping the track units is shown in Figs. 17 to 20. Preferably and as shown such a frame is provided at each side with, for instance, four pairs of gripping dogs or claws 24, 25

projecting transversely through the sides of the frame D' and adapted to engage below the head of the rails of the track units to be seized. The dogs or claws of the two sides are arranged transversely in alignment and 70 are all operated simultaneously. The gripping claws 24, 25 of opposite pairs are connected by links 24^a 25^a to eccentric pins mounted diametrically opposite each other on one of two meshing spur wheels 26, 26'. 75 The spur wheels 26 of the several sets on one side are mounted on a common shaft 27 operated by either of two hand wheels 28 secured as shown in Figs. 18, 19 at opposite 80 sides of the frame D' on a common actuating shaft 29. The rotary motion imparted to the shaft 29 by one of the hand wheels 28 is transmitted by spur gearing 30 and a worm 31 to a worm wheel 32 mounted on the shaft 27. The spur wheels 26 being thus operated will each cause its companion spur wheel 26' to rotate in the opposite direction so that the claws 24 will be drawn in and the claws 25 pushed out (see Fig. 20) thus 85 jointly closing on the head of the rail R of the track unit. Rotation of a hand wheel 28 in the opposite direction will cause the claws 24 and 25 to open and thereby to release the 90 rails R.

The arrangement and construction of the 95 cantilever or bridge C including its motor driven crane crab E are illustrated more particularly in Figs. 1 and 5 to 9. It is as stated mounted on the crane truck B and provided with a long arm C' projecting forward over the truck and the roadbed so as to allow an assembled track unit to be run out clear thereof and lowered. The inner shorter cantilever arm C^a is weighted in the usual manner to assist balance.

As shown in Fig. 9 the pillar structure C is arch-shaped to provide room for the crane or laying crab E and the passage of the track section RS and is rigidly supported on the sides of the truck. As shown in Figs. 6 and 8, the arms C' and C^a of the cantilever are tapered or contracted to outward and inward, respectively; the object of the taper on the rear arm C^a being to enable the gantry structure D to travel over or, rather, to house a substantial portion of the arm C^a at the laying end of the train, and the grip frame or grab D' to approach the grip frame E' as closely as possible for their 105 cooperation.

The laying crab E (Figs. 7, 8, 9) runs on rails 33 arranged on the inside of the cantilever and is provided with a driving motor 34 connected by a reducing gear directly to the front axle of the crab. A hoisting motor 35 drives the winding drum 36 working the ropes 35^a over pulley blocks, suspended from which is the grip frame E'. Only two floating sheaves 37 carry the frame E' so 110 that lateral displacement of the said sheaves 115 120 125 130

out of the centre line of gravity of the frame E' and the load carried thereby enables such load to be tilted laterally at will.

For this purpose and as shown in Figs. 5 21, 22 and 23 the frame E' is suspended or supported at each point of suspension on the wheels of a transversely arranged carriage 38 which is attached to the sheaves 37. At one end the carriage is formed into or 10 has secured to it a guide rod 38^a while at the other end a screw threaded spindle 38^b is fitted to said carriage. A worm wheel 39 mounted as a nut on the spindle 38^b when rotated by means of the worm 40 causes the 15 carriage to be moved axially, that is transversely to the frame, and thereby to displace the point of suspension laterally. The worms 40 of the two suspension devices are mounted on a common shaft 41 which 20 is operated by means of the hand wheel 42.

The frame E' is fitted with gripping claws 24, 25 in an analogous manner as described hereinbefore in connection with the grip frame D' of the travelling gantry.

25 In operation, if it is desired to lay a new track, sections RS of the assembled track are stacked on the successive railway trucks A as shown and picked up in successive order by the grab D' attached to the gantry D which travels on the runways 1, 3, 4 on top of said trucks. The gantry crane D is then propelled on to the cantilever truck B and over the arm C² of the cantilever, this being possible due to the outer structure of the 30 gantry D being wider than that of the tapering arm C², which latter is thus enabled to telescope, so to say, into the gantry to the desired extent as shown in Figs. 5 to 8, after having lowered the assembled track with its 35 sleepers over the truck A', and is caused to deposit it on top of the cantilever truck. The crane crab E on the cantilever C is then caused to pick up this section of assembled track which is then run out on the cantilever 40 arm C² and the section of track is lowered out and laid on the ground. In the meantime the first trolley crane D referred to has travelled back on the railway trucks A' and A to pick up its next load of assembled track 45 and so the cycle of operations proceeds until all the sections of assembled track are transferred from the trucks A to their laid positions, the train progressing forward on the 50 newly laid sections of railway track as the 55 work proceeds.

In taking up sections of old laid railway track and laying new units in their place, the old assembled sections with their sleepers are raised by means of the cantilever crane 60 crab E and transferred on to the top of the cantilever truck B while the travelling gantry D on the railway trucks travels with its load as before and lays the new track unit on top of the removed section of track. 65 These operations can also be reversed, the

old track being placed on top of the new length already in position on the cantilever truck. The cantilever crane crab E then picks up this new section of track and lays it in joining position to the existing laid track. In the meantime the gantry crane D picks up the old section of track from the cantilever truck B and transfers it on to one of the trucks A and so the operation proceeds until all the new track units are removed from their trucks and are replaced by the old sections of removed tracks, the train progressing along the previously existing track as the new track units are laid. The old sections of track are then transferred to the depot. When not laying track it is found convenient and desirable to boost or support the longer overhanging portion of the cantilever C by means of a railway truck provided if desired with a bolster or support which will run on the railway proper. Said truck may be subsequently side-tracked and shunted on to the train and loaded up with sections of removed track.

70 It will be readily understood that a train arranged according to this invention could without material modifications be employed with equal facility and usefulness for the transport and rapid handling of other materials than those herein specified. Moreover, the details of construction hereinbefore described as well as the arrangement and operation may, as will be obvious be easily varied by those skilled in the art without departing from the spirit or nature of this 75 invention which should not therefore be deemed limited to the specific example or application illustrative of its performance.

90 I claim as my invention:

1. Railway rolling stock for laying, taking up or re-laying railway tracks from assembled track units or sections, comprising a train of trucks coupled together in line and having track sections attached to their respective floors or decks and connected with one another to form a single continuous rail track; a gantry adapted to travel freely along said track from one end of the train to the other; and a laying crab at the laying end of the train adapted to receive 105 track units from or feed them to the gantry.

110 2. Railway rolling stock, according to claim 1, in which the crab is carried by a cantilever extending into the path of the gantry; and in which the reception and feeding of the track units by and from the crab take place substantially on a level with the decks of the trucks.

115 3. Railway rolling stock, according to claim 1, in which the track sections are mounted on the consecutive trucks with spaces between them for the stacking of the track units; and in which the gantry is adapted to travel along the track and over the stacked units.

4. Railway rolling stock for laying, taking up or re-laying railway tracks from assembled track units or sections, comprising a train of trucks coupled together in line and having track sections attached to their respective floors or decks and connected with one another to form a single continuous rail track, the track sections on successive trucks being mounted with spaces between them for the stacking of the track units; a gantry adapted to travel freely along said track and over the stacked units from one end of the train to the other; a cantilever at the laying end of the train extending into the path of the gantry; and a laying crab carried by the cantilever adapted to receive track units from or feed them to the gantry substantially on a level with the decks of the trucks.
5. Railway rolling stock for laying, taking up or re-laying railway tracks from assembled track units or sections, comprising a train of trucks coupled together in line and having track sections attached to their respective floors or decks and connected with one another to form a single continuous rail track, the track sections on consecutive trucks being mounted with spaces between them for the stacking of the track units; a gantry adapted to travel freely along said track and constructed to form a bridge or arch over and clear of the stacked track units; a cantilever at the laying end of the train having an arm which overhangs said track and which is constructed to enable the gantry and the said arm itself to house one another in their co-operative position; and a crab carried by said cantilever to receive track units from or feed them to the gantry.
6. Railway rolling stock for laying, taking up or re-laying railway tracks from assembled track units or sections, comprising a train of trucks coupled together in line and having track sections attached to their respective floors or decks and connected with one another to form a single continuous rail track, the track sections on consecutive trucks being mounted with spaces between them for the stacking of the track units; a gantry adapted to travel freely along said track and constructed to form a bridge or arch over and clear of the stacked track units; a cantilever at the laying end of the train having a forward arm which overhangs the road bed and a rear arm which overhangs the track; a crab carried by the cantilever to receive track units from or feed them to the gantry; and a runway for the crab laid over the entire length of the cantilever coaxially with and at a relatively slight distance above the said track.
7. Railway rolling stock for laying, taking up or re-laying railway tracks from assembled track units or sections, comprising a train of trucks coupled together in line and having track sections attached to their respective floors or decks and connected with one another to form a single continuous rail track; and bridge rails between the track sections of consecutive trucks each composed of two members connected by a readily-detachable substantially-universal joint, one of said members being universally jointed to the rail of one truck and the other member being slidably attached to the rail of the other truck.
8. Railway rolling stock for laying, taking up or re-laying railway tracks from assembled track units or sections, comprising a train of trucks coupled together in line and having track sections attached to their respective floors or decks and connected with one another to form a single continuous rail track; a gantry adapted to travel freely along said track and provided with a hoisting gear and with a grip frame suspended therefrom; and mechanism for adjusting said frame laterally transversely of the trucks.
9. Railway rolling stock for laying, taking up or re-laying railway tracks from assembled track units or sections, comprising a train of trucks coupled together in line and having track sections attached to their respective floors or decks and connected with one another to form a single continuous rail track; a gantry adapted to travel freely along said track; a hoisting crab at the laying end of the track for cooperation with the gantry; and a grip frame suspended from the crab and provided with means enabling lateral displacement of its points of suspension out of the center line of gravity, so that said frame and the load it carries may be tilted laterally.
10. Railway rolling stock for laying, taking up or re-laying railway tracks from assembled track units or sections, comprising a train of trucks coupled together in line and having track sections attached to their respective floors or decks and connected with one another to form a single continuous rail track; a gantry adapted to travel freely along said track; and a grip frame carried by the gantry having laterally-operable jaws arranged in pairs at opposite sides.
11. Railway rolling stock, according to claim 10, in which the several pairs of jaws provided on the grip frame are operable simultaneously to grip or to release the two rails of a track section by means of toothed gearing and crank mechanism.
12. Railway rolling stock for laying, taking up or re-laying railway tracks from assembled track units or sections, comprising a plurality of trucks coupled together in line and having track sections attached to their respective floors or decks and connected with one another to conjointly form a single continuous rail track; a power-driven gantry

adapted to travel along said track; flexible conductors associated with the several trucks for supplying current to the track sections thereon; a portable power house connected to travel with the track-carrying trucks and from which said conductors are supplied; and current-collecting means carried by the

gantry for engagement with the track rails. In testimony whereof I affix my signature in presence of two witnesses.
